UNITED STATES PATENT OFFICE.

HENRY BRADY, OF BLOOMFIELD, AND ADIN W. HILSINGER, OF ORANGE, NEW JERSEY,
ASSIGNORS TO HENRY BRADY, INC., A CORPORATION OF NEW JERSEY.

PAPER-BOX-FORMING MECHANISM.

Application filed June 30, 1922. Serial No. 572,051.

To all whom it may concern:

Be it known that we, HENRY BRADY and ADIN W. HILSINGER, citizens of the United States, residing at Bloomfield and Orange, in the county of Essex and State of New Jersey, have invented certain new and useful Improvements in Paper-Box-Forming Mechanism, of which the following is a specification, reference being had therein to the accompanying drawing.

Our invention relates to improvements in the manufacture of containers, and more particularly has reference to a machine adapted to form boxes out of a sheet of heavy paper, such as card, and is in part a continuation of our previous patent applications serially numbered 184,202, and 337,302.

Referring to the accompanying drawing, we have illustrated in perspective, parts being broken away, a suitable form of forming device, embodying an application of our invention.

2 indicates the driving chain upon the sprocket 3, upon the shaft 4 which carries a cam 5 within which passes the roller 6 of the shaft 7 the lower end of which is bifurcated at 8 to clear the shaft 4, thus providing a vertical reciprocating movement for the male die 9.

Upon the same shaft at one end is mounted the cam 10 within which a roller upon the lever 11 operates to oscillate the beam 12 pivoted in the frame of the machine as indicated at 13, the opposite end of the beam 12 being provided with a hole through which the shaft 14 passes. 15—16 indicate stops for coiled springs such as 17—18 which cushion the lever 12 between said stops 15—16 while at the same time vertically reciprocating the shaft 14 which carries the ejector 19 concentrically reciprocable within the female former 20 and its shaft or stem 21 which is held by the yoke 22 vertically slidable upon the standards or rods 23—23'. This yoke 22 is pivotally connected to the lever 24, at the lower extremity of which is a roller 25 engaging the cam 26 upon the shaft 4.

50 The yoke 27 is driven by the rod 28 engaging the cam 29 upon the shaft 4 and operates the stitching mechanism through the lever 30, pivoted at 31. Associated with this stitching mechanism, however, is the corner folding mechanism of the former 20 and

comprises a pair of rods or a fork such as 32 at the inner ends of which are the rods 33—33' pivoted upon the shaft 34. The outer end of the lever 30 is provided with rollers such as 35—35' which ride upon the upper surface of the rods 32 as shown, thereby oscillating the other extremities 33—33' and causing the hinged flaps 36—36' to operate against the springs mounted in the hinges thereof, which said springs tend to normally keep the flaps open, one end of one of the springs being indicated by the reference character 37.

In the operation of the forming device, the two upper plungers 14—21 pass downwardly together, the plunger 14 pressing the blank upon the male die 9 while the plunger 21 further forms the blank, after which the corners are turned over by the hinged flaps 36—36' operated by the levers 33—33' as aforesaid. Upon the return stroke of the plungers 14—21 the plunger 21 moves first, leaving the plunger 14 to clear the die 9 of the tray formed therein. This insures against any sticking of the formed box within the die. The several cams and connecting rods, it will be also observed, are more or less duplicated at opposite sides of the machine, thus producing a properly balanced structure, and the extent to which this feature of the invention may be carried out is more or less a matter of judgment in the design of any particular machine.

Of course it will be understood that various modifications may be made in the construction and arrangement of parts without departing from the spirit of the invention as claimed.

We claim:

1. In combination with a blank forming device of the class described, a male and female die for forming the blanks, a gripper rod normally retracted from one of said dies and guided through the centre of one part of the same to force a blank toward the other of said dies before said blank is formed, means to reciprocate said rod, and means external of said dies for folding the corners of said blank.

2. In combination with a blank forming device of the class described, a male and female die for forming the blanks, a gripper rod normally retracted from one of said dies and guided through the centre of one

part of the same to force a blank toward the other of said dies before said blank is formed, means to reciprocate said rod, and means external of said dies for folding the corners of said blank, said means comprising flaps hinged at the beveled corners of said female die and oscillating fingers for

laying said flaps over the corners of said blank.

In testimony whereof we hereunto affix 10 our signatures.

HENRY BRADY.
ADIN W. HILSINGER.
